GOLFING ACCESSORY FOR POSITIONING GOLF TEE

Dwight E. Hottle, Akron, Ohio

Application June 8, 1955; Serial No. 514,083

4 Claims. (Cl. 273—33)

This invention relates to golfing accessories, and in particular, relates to a golfing accessory that is capable of aiding the user thereof in positioning the customary golf tee used in playing golf.

In the game of golf, a player is permitted, on his initial stroke on each hole, to use a golf tee for elevating the golf ball a certain distance above the ground. While various shapes and forms of tees have been proposed in the past for this purpose, the normal form of golf tee comprises an elongated cylindrical member, having an enlarged axial end formed with a cup surface for reception of the golf ball, and having an axially-spaced pointed end which is intended to pierce the ground so as to horizontally space the cup end of the golf tee at a slightly elevated position above the ground.

Under normal conditions, the user of a golf tee merely pushes the pointed end of the tee into the ground by manual force to effectuate positioning of the golf tee. However, during a dry spell, when the ground becomes hard, it is oftentimes difficult to effectuate such positioning, because sufficient downward pressure cannot be applied centrally of the cup area to cause the golf tee to pierce the hard ground. Accordingly, tees will be oftentimes broken or improperly positioned during such periods when the ground is hard.

As a further disadvantage of such manual forms of positioning golf tees as are above described, it will be noted that no means are provided for positioning the cup head at a uniform distance above the ground on repeated occasions of use, with the result that the golf ball will invariably be located at different elevations above the ground upon teeing up on successive holes. Such inaccuracies in positioning the golf tee frequently result in detrimental variation in the trajectory flight of the golf ball when the same is struck by the golfer.

In addition to the aforementioned difficulty in teeing a golf ball, a golfer has occasion frequently to tighten the spikes of his golf shoes that are used in the playing of the game of golf. Failure to tighten these spikes or cleats promptly oftentimes results in the same being prematurely separated from the shoe of the user during the playing of a round of golf.

Accordingly, it is one object of this invention to provide a tee positioning device that enables the user thereof to accurately position the head of a golf tee at a uniform elevation at each period of use.

It is a further object of this invention to provide a tee positioning device that enables the user thereof to position a golf tee in hard, dry ground without damage to the golf tee.

It is a still further object of this invention to provide a golfing accessory that functions to accurately position the head of a golf tee at a predetermined elevation above any ground surface, whether the same be hard or soft, and further characterized by the fact that the same is capable of tightening golf spikes or cleats that are provided on golfing shoes.

It is a still further object of this invention to provide

2

a golfing accessory of the character above described, that is of simplified construction having a minimum number of component parts and being capable of being mass-produced at a relatively low unit cost.

5 These and other objects of the invention will become more apparent upon a reading of the following brief specification, considered and interpreted in the light of the accompanying drawings.

Of the drawings:

10 Figure 1 is a perspective elevation illustrating a golfing tee being supported in the improved positioning device that is held in the hand of a user.

Figure 2 is an elevation view illustrating the use of the improved positioning device for positioning a golfing tee into a ground surface.

15 Figure 3 is a sectional view taken on the lines 3—3 of Figure 2.

Figure 4 is a view taken on the lines 4—4 of Figure 2.

20 Figure 5 is a perspective view illustrating the operation of a modified form of the invention for tightening golf spikes or cleats.

Figure 6 is a sectional view of the modified form of the invention.

25 Figure 7 is a view taken on the lines 7—7 of Figure 6.

Referring now to the drawings, and in particular, to Figures 1 and 2 thereof, the improved tee holder, generally designated as 10, is shown receiving a golf tee T so that the pointed end T_p thereof projects therefrom for positioning in ground G upon application of force by

30 hand H.

Structurally, the tee holder 10 is shown as being defined by a gripping handle 11 and a circular body portion 12 that joins with the gripping handle 11 so as to form therewith a T-shaped holder 10; the arrangement being such that finger cut-outs 13, 13 facilitate gripping of handle 11, while an enlarged foot portion 14 is provided on the free end of the body portion 12 for engagement with ground G when the component parts are positioned as shown in Figure 2.

35 40 For the purpose of receiving the golf tee T, the body portion 12 includes an elongated tapered slot 20 that extends inwardly from the exterior surface of body portion 12 to provide a complementally-shaped recess for the golf tee T.

45 50 To the end of effectuating this complemental relationship between the slot 20 and the golf tee T, the slot 20, best illustrated in Figure 2, is shown in cross-sectional configuration as having an enlarged head opening 21, the vertical height of which is defined by the horizontal surface 12a of the body section 12; while the opposite free end 22 of the slot 20 is shown as being of reduced cross-sectional area so as to be receivable about the stem portion T_s of the golf tee T.

55 60 For the purpose of clarity, the point of juncture of the slot 20 with the exterior surface of the body portion 12 will be hereinafter designated as opening 23, while the point of juncture of the slot 20 with the exterior surface of the foot portion 14 will hereinafter be designated as opening 24.

65 It is believed apparent that a certain amount of clearance will exist between the slot 20 and the golf tee T to thus permit accommodation of different size tees. However, in view of the direct force application through surface 12a, such clearance will not affect the positioning of the tee.

65 In use or operation of the improved tee holder 10, the user thereof merely grips the handle portion 11 so as to present the opening 23 thereof upwardly; and with the device 10 in this position, a golf tee T may be easily inserted into the slotted opening 20 by passing the same through the opening 23 that is provided on the exterior surface of the body portion 12, so as to permit the golf tee T to be received within the slot 20, as best shown

in Figures 1 and 2 of the drawings. With the golf tee T positioned as just described, the pointed end T_p of the tee will project as shown in Figure 1 of the drawings, and the user at this time merely places the thumb or index finger of his hand as desired, over the opening 23 so as to retain the golf tee T within the confines of the complementally-shaped slot 20. In this position the user merely pushes the pointed end T_p of the tee into the ground, and during the time that the pointed end of the tee is being pushed into the ground as just described, it is apparent that the head T_h will be urged against the flat area 12a of the body portion 12, with the result that this surface will transmit the requisite pushing force to the golf tee to cause the pointed end T_p thereof to pierce the ground, whether the same be hard or soft.

In every case, the extent of the degree to which the golf tee T will pierce the ground G will be fixed as a result of the exterior surface of the foot portion 14 coming in contact with the ground G, as best shown in Figure 1. At such time as this contact is made between the foot portion 14 and the ground G, further pushing movement of the tee into the ground will be impossible; and accordingly, the tee will be properly positioned at such time as the foot portion 14 engages the ground G. When such contact has been made, the user merely removes his thumb from its position of covering over opening 23 and slides the holder 10 to one side so as to permit the removal of the same from its surrounding relationship with respect to the golf tee T. At this time, the golf tee will be accurately positioned and the golf ball may be placed upon the same in known manner.

It will be seen from the foregoing that there has been provided a new and novel type of golf tee holder that will accurately and uniformly position a golf tee so that the head or ball supporting portion thereof is automatically fixed in a predetermined elevation above the ground in each case of usage. It has been further shown how the golf tee holder above described, is of simplified construction, thus indicating that the same can be easily produced on a mass production basis. While the sectioning of the drawings of Figures 1 to 4 of the invention illustrate that the preferred embodiment of the invention is made of plastic material, it is to be understood that any other suitable material could be used in this regard, it being apparent that the structural qualities of the material employed do not affect the operation of the device.

The modified form of the invention illustrated in Figures 5, 6 and 7 of the drawings is similar in every respect to that previously described and shown in Figures 1 to 4 of the drawings, with the single exception that a modified type of foot portion 14 is provided. Accordingly, where indicated, like numerals designate like parts.

Referring now to Figure 5 of the drawings, it will be seen that the modified tee holder 10 is shown positioned so as to effectuate a tightening action upon a cleat C that is provided on the usual golf shoe S.

As best shown in Figures 6 and 7, the modified foot portion 14 includes a concave surface 30 provided on the ground engaging side of a foot member 14 and joining with the slot 20 as at 31, to define a rectangular cutout that permits passage of the tee T. To the end of effectuating tightening action of the cleat C, the concave surface 30 further includes a pair of tightening pins 32, 32 that are carried by the foot portion 14 so as to have the projecting ends 32a, 32a thereof capable of being received in the openings 40, 40 of the cleat member C. In this manner, when the cleat C is positioned as shown

in Figure 6 with the spike portion being inserted in the slot 20, the openings 40, 40 of the cleat C may be engaged by the projecting ends 32a, 32a of the foot portion 14; and turning of the handle 11 will permit the cleat C to be tightened with respect to the golf shoe S.

It is believed apparent that the presence of the pins 32, 32 will not affect the operation of the device as a tee holder, in view of the fact that the plane of the same does not materially extend below the ground-engaging plane of the foot portion 14, to thus interfere with the ground-engaging function of the same.

It follows that other modifications of the invention may be resorted to without departing from the spirit thereof or the scope of the appended claims.

15. What is claimed is:

1. A tee-positioning device comprising; a unitary body having a ground-engaging surface and a blind bore extending inwardly of said surface and defining an elongated cavity surrounded by a wall having an internal end; said wall of said blind bore having an elongated opening therethrough that extends between the ground-engaging surface of said body and the internal end of said bore; said bore increasing in dimension along its length and having its largest dimension interiorly of said body adjacent the internal end of said bore.

2. A tee-positioning device comprising; a unitary body having a ground-engaging surface and a blind bore extending inwardly of said surface and defining an elongated cavity surrounded by a wall having an internal end; said wall of said blind bore having an elongated opening therethrough that extends between the ground-engaging surface of said body and the internal end of said bore; said bore increasing in dimension along its length and having its greatest width adjacent the internal end of said bore.

3. A tee-positioning device comprising; a unitary body having a ground-engaging surface and a blind bore extending inwardly of said surface and defining an elongated cavity surrounded by a wall having an internal end; said wall of said blind bore having an elongated opening therethrough that extends between the ground-engaging surface of said body and the internal end of said bore; said bore increasing in dimension along its length and having its largest dimension interiorly of said body adjacent the internal end of said bore; said opening also increasing in dimension along its length and having its greatest width adjacent said internal end of said bore.

4. An accessory device of the character described; comprising, a unitary body of generally cylindrical configuration having a handle end and a flat opposed axial end surface, said body having a blind bore extending inwardly of said surface and defining an elongated cavity that is surrounded by a wall having an internal end; said wall of said blind bore having an elongated opening therethrough that extends between said flat axial end surface of said body and said internal end of said bore; said bore increasing in dimension along its length and having its largest dimension interiorly of said body adjacent the internal end of said bore.
